WILLIAM M. DOTY, OF NEW YORK, N. Y.

Letters Patent No. 77,598, dated May 5, 1868.

IMPROVED CLOTHES-PIN.

The Schedule referred to in these Letters Patent and making part of the same.

TO WHOM IT MAY CONCERN:

Be it known that I, WILLIAM M. DOTY, of New York, in the county of New York, and State of New York, have invented certain new and useful Improvements in Clothes-Pins; and I hereby declare the following to be a full, clear, and exact description of the same, reference being had to the accompanying drawing, which represents a perspective view of a clothes-pin made in accordance with my invention.

My invention consists of a clothes-pin composed of a hook and stock or handle combined, the said parts being placed at right angles, or transversely to each other, and forced together by means of a spiral or other spring-device, as to confine and hold firmly the rope or other article placed between them. The hook and handle have, of course, a play or movement towards or away from one another, and are held together by the spring which exerts the yielding pressure needed in order to confine the article inserted between them, and at the same time to allow them to be separated when it is desired to remove the article.

In the drawing; A represents the handle or stock of the pin, and B the hook, placed at right angles thereto, its square shank *a* passing through a hole or opening, of corresponding size, in the stock, in which it fits loosely, so as to allow the hook to have the necessary transverse play towards or away from the handle. Upon that portion of the shank *a* which extends through the stock, and projects from its other side, is wound a spiral spring, *b*, one end of which bears against the stock, the other being confined by pins or studs, *c*, on the end of the shank.

By the action of this spring, the hook B and stock A are pressed together, so as to tightly hold any article, the rope, C, for instance, placed between them, as will be understood without further explanation.

Instead of the spiral spring, vulcanized rubber, or other elastic and yielding devices may be employed. The arrangement of the hook and stock may also be varied without departing from the principle of my invention; as, for instance, the hook can be made of wood, wire, or other substance, so forked as to embrace or be supported in grooves formed on the exterior of the stock, or the arrangement may be otherwise modified, all that is needed being that the two parts should have the requisite transverse play towards or away from each other.

I do not claim broadly the use, as a clothes-pin, of a clamp actuated by a spring, nor the mode of forming one of the clamping-devices on a spindle passing at right angles through the other; but having now described my invention, and the manner in which the same is or may be carried into effect.

What I claim, and desire to secure by Letters Patent, is—

1. A clothes-pin, composed of a stock, hook, and spring, combined, as herein specified, the hook having a play at right angles, or transverse to the stock, in the manner described.
2. The arrangement of the hook and stock, so that the former shall pass through the body of the stock or be supported upon the exterior of the same, as and for the purpose herein set forth.

In testimony whereof, I have signed my name to this specification before two subscribing witnesses.

W. M. DOTY.
